Attorney

UNITED STATES PATENT OFFICE.

HARRY L. KIRKPATRICK, OF PUEBLO, COLORADO, ASSIGNOR OF ONE-THIRD TO
WALTER M. RANKIN, OF SPRINGFIELD, MISSOURI.

SWITCH.

1,081,839.

Specification of Letters Patent.

Patented Dec. 16, 1913.

Application filed December 3, 1912. Serial No. 734,740.

To all whom it may concern:

Be it known that I, HARRY L. KIRKPATRICK, a citizen of the United States, residing at Pueblo, in the county of Pueblo 5 and State of Colorado, have invented new and useful Improvements in Switches, of which the following is a specification.

This invention relates to improvements in railway switch stands and especially with 10 reference to improvements in the operating handle or lever and means for locking the same so as to cause the handle or lever to lock the switch rail, the object of the invention being to provide an improved switch 15 stand in which the handle or lever may be moved to any extent necessary to insure the placing of the switch point against the rail and avoid the necessity of having to disconnect the bridle rods or to rearrange the adjustment of the stand in order to vary the 20 throw of the switch, the invention consisting in the construction, combination and arrangement of devices, hereinafter described and claimed.

25 In the accompanying drawing:—Figure 1 is a perspective view of a switch stand constructed in accordance with my invention. Fig. 2 is a horizontal sectional view of the same on the plane indicated by the 30 line *a—a* of Fig. 1. Fig. 3 is a detail vertical sectional view of the same on the plane indicated by the line *b—b* of Fig. 1. Fig. 4 is a view similar to Fig. 2, showing a modification. Fig. 5 is a detail perspective view 35 of the handle or lever.

In the embodiment of my invention here shown, there is a stand or tripod 1 which comprises upwardly converging legs 2, the base 3 on which the legs are mounted, a 40 bearing 4 connecting the lower portions of the legs and an adjusting plate 5 to which the upper ends of the legs are secured. This adjusting plate is circular and is provided with peripheral locking spurs or 45 teeth 6.

The staff 7 which carries the target 8 and signal lantern 9 is mounted in a circular bearing 10 with which the adjusting plate is provided and also in the bearing 4. This 50 staff has the usual crank arm 11 to which the bridle rods are connected which operate the movable switch point. The bridle rods and the switch point are not here shown as they are of the usual well-known construction.

The handle or lever 12 comprises an inner member 13 which is secured to the staff at a point immediately above the adjusting plate and a movable outer member 14 which is pivotally connected as at 15 to the outer 60 end of the inner member. The pivot 15 is at some distance from the inner end of the outer member and the inner member 13 is provided at its outer end with a vertical arm 16 which has a vertical slot or recess 65 in which the inner end of the outer member 14 operates. The arm 16 and the inner end of the member 14 have openings which are coincident when the member 14 is in vertical position so that the shackle of a suitable 70 padlock 17 may be passed through the said openings and the padlock employed to lock the member 14 in such vertical position. The member 14 is provided on its inner or under side with locking teeth 18 which may 75 be engaged with the teeth 6 of the adjusting plate at many points around the periphery of the adjusting plate so as to lock the handle or lever and, hence, also the staff 80 and its crank arm.

It will be understood that the switch point, being connected to the crank arm 11 by the usual bridle rods may be moved to any extent required to cause it to lie closely against the track rail by moving the handle 85 or lever 12. Thus, the handle or lever of my improved switch stand is not restricted in its movements to any certain adjustments but may be moved as far as may be required to effectually set the switch point under any 90 circumstances. As soon as the switch point has been set the outer member of the handle or lever is turned down so as to engage the teeth of the adjusting plate and lock the switch and the padlock may be then applied 95 so as to secure the handle or lever in locked position.

To protect the operating parts of my improved switch stand from the weather, I provide a conical cap 19 which is secured 100 on the inner member of the handle or lever for movement therewith and has an opening in its apex through which the staff extends.

While I have herein shown and described a preferred form of my invention, I would have it understood that changes may be made in the form, proportion and construction of the several parts without departing from the spirit of my invention and within the scope of the appended claims.

When it is desired to limit the extent of movement of the crank arm, a pair of stops 20 may be employed, which are provided with set screws 21, to secure them in place 5 on the adjusting plate, the latter being provided with threaded openings for engagement by the set screws.

I claim:—

- 10 1. A railway switch stand of the class described having a staff provided with a crank arm, an adjusting plate through which the staff extends and in which the same revolves, the said adjusting plate having peripheral locking teeth, and an operating lever or handle comprising an inner member secured to the staff and arranged to sweep over the adjusting plate and an outer member pivotally connected to the inner member and adapted to engage the teeth of the adjusting 15 plate at any required point.
- 20

2. A railway switch stand of the class described having a staff provided with a crank arm, an adjusting plate through which the staff extends and in which the same revolves, the said adjusting plate having peripheral 25 locking teeth, and an operating lever or handle comprising an inner member secured to the staff and arranged to sweep over the adjusting plate, an outer member pivotally connected to the inner member and adapted 30 to engage the teeth of the adjusting plate at any required point, and means to secure the outer member of the handle or lever in locking position.

In testimony whereof I affix my signature 35 in presence of two witnesses.

HARRY L. KIRKPATRICK.
